UNITED STATES PATENT OFFICE.

THEODORE A. KOCHS, OF CHICAGO, ILLINOIS.

DESIGN FOR AN ARM-REST SUPPORT.

SPECIFICATION forming part of Design No. 16,251, dated September 15, 1885.

Application filed June 16, 1885. Term of patent 7 years.

To all whom it may concern:

Be it known that I, THEODORE A. KOCHS, a citizen of the United States of America, residing at Chicago, in the county of Cook and State 5 of Illinois, have invented a certain new and useful Design for Arm-Rest Supports, of which the following is a specification, reference being had therein to the accompanying drawing.

10 My invention relates to a design for barbers' and other like chairs.

The invention consists of the representation of an elephant-head, such representation forming a part of the front uprights of the arms of 15 the chair.

In the accompanying illustration I have shown a barber-chair and foot-rest in perspective.

The general form and appearance of the 20 chair may be of any suitable design; and my invention relates only to the design of the front uprights of the arms of the chair.

As represented in the accompanying illustration, each of these uprights is curved, and

at its upper end designed to represent the head 25 of an elephant. The representation herewith made shows the elephant's trunk as resting upon the lower portion or base of the upright; but it will be understood that I do not wish to confine myself to such an arrangement, as 30 it might be slightly changed without departing from the invention.

In the accompanying illustration, A represents the chair; B, the foot-rest; C, the chair-arms; D, the front uprights therefor; E, the 35 elephant-head; F, the trunk, and G the tusks.

What I claim is—

A design for arm-rest supports, which consists of a curved upright and the representation of an elephant head, the trunk resting 40 upon the curved uprights, as set forth.

In testimony whereof I affix my signature in presence of two witnesses.

THEODORE A. KOCHS.
